(57) **CLAIM**

The ornamental design for a garment and accessories organizer, as shown and described.

DESCRIPTION

FIG. 1 is a front perspective view of an embodiment of a garment and accessories organizer, embodying our new design.

FIG. 2 is a front plan view of the same organizer.

FIG. 3 is a left side plan view thereof.

FIG. 4 is a back plan view thereof.

FIG. 5 is a right side plan view thereof, which is a mirror image of FIG. 3.

FIG. 6 is a top plan view of thereof.

FIG. 7 is a bottom plan view thereof.

FIG. 8 is a perspective view of the same organizer when it is folded.

FIG. 9 is a front view of the same organizer when it is folded.

FIG. 10 is a left side view of the same organizer when it is folded.

FIG. 11 is a back view of the organizer when it is folded.

FIG. 12 is a right side view of the same organizer when it is folded.

FIG. 13 is a top view of the same organizer when it is folded.

FIG. 14 is a bottom view of the same organizer when it is folded; and,

FIG. 15 is a back perspective view of the same organizer showing the lengthwise zipper when it is open.

The broken lines and hash patterns in the figures depict environmental structures and do not form a part of the claimed design.
